UNITED STATES PATENT OFFICE.

ROBERT NORRIS, OF WYTHEVILLE, VIRGINIA.

WINDOW-WEATHERPROOFING.

1,341,434.

Specification of Letters Patent.

Patented May 25, 1920.

Application filed September 19, 1919. Serial No. 324,781.

To all whom it may concern:

Be it known that I, ROBERT NORRIS, a citizen of the United States, residing at Wytheville, in the county of Wythe and 5 State of Virginia, have invented certain new and useful Improvements in Window-Weatherproofing, of which the following is a specification.

This invention relates to certain new and 10 novel improvements in windows provided with sliding sash-frames, and has special reference to the novel construction of the sash-frames and their connections with the window frame, whereby when the sash 15 frames are in a closed and locked position an absolutely air-tight and weather-proof window is provided, at the same time providing means whereby the sash-frames may be easily manipulated so as to furnish a 20 maximum amount of ventilation and be readily removed within a room for cleaning, repairs or any other desirable purpose.

The prime object of my invention is to 25 provide a simple, durable, economical and efficient window frame, and sliding sashes fitted within the frame, so constructed that wind, dust, rain, or other foreign matter cannot enter a room when the sashes are locked in closed position, thereby constituting 30 a weather proof window and preventing the sashes from rattling.

Another object of this invention is to furnish means whereby both the upper and lower sashes may be easily removed from 35 the window frame within a room for cleansing the panes, thus eliminating the inconvenience and danger, as well as avoiding the public gaze to which window cleaners are usually subjected during the window cleaning 40 operation.

A further object of the invention is to furnish novel means adapted to be used for 45 ventilating purposes, which will permit the entrance into a room of a sufficient supply of fresh air without producing a direct draft or in any other manner subjecting the occupants to inconvenience, discomfort, or danger, and at the same time preventing the entrance of rain or snow within the room.

50 Another object of the invention is to so construct the upright side rails of each sash that the sash cords may be easily and quickly attached or removed therefrom, and when said cords are properly attached to the sashes 55 they will rest in alinement with the pulleys

secured at one side of each slideway at the upper end portion of the window frame.

Another object of this invention is to provide novel locking and interlocking means in connection with the sashes and window 60 frame, whereby the parts are removably and detachably secured together in their proper relative positions.

The foregoing and such other objects as may appear from the ensuing description 65 are accomplished by the novel features of construction, arrangement, combination and location of the parts hereinafter more fully described, illustrated in the accompanying drawings, and particularly pointed out in 70 the claims appended hereto, it being understood that slight changes in the form, proportion, and minor details of the construction may be resorted to without departing from the spirit or sacrificing any of the ad- 75 vantages of the invention.

Reference now being had to the accompanying drawings which form a part of this specification and in which similar numerals of reference designate like parts throughout 80 the several views, it will be seen that:—

Figure 1, is a perspective of the improved means embodying my invention.

Fig. 1^a, is a detail perspective of a securing bar or link.

Fig. 2, is a central vertical section of the device shown in Fig. 1.

Fig. 3, is a vertical section, taken on the line 3—3, Fig. 1, showing the lower sash in its closed position.

Fig. 4, is an enlarged edge or side elevation of the lower sash frame and its connections removed from the window frame.

Fig. 5, is a front face elevation of a cover plate for the cord securing portion of the 95 sash frame.

Fig. 6, is an enlarged side elevation of the parting strip, showing the two sections of the strip locked together at the central portion of the window with the upper and 100 lower portion thereof broken away.

Fig. 7, is a front face elevation of the parting strips shown in Fig. 6, and

Fig. 8, is a sectional elevation of one of the wear bearing plates secured within a re- 105 cess formed at each side of the window frame.

In carrying out the construction and arrangement embodying my invention as illustrated, and which shows a preferred 110

construction, the numeral 1, indicates a window frame of the standard well known construction provided with sash weights 2, cords 3, and pulleys 4, each of said pulleys being 5 suitably secured at one side of each of the slideways 5 and 6, at the upper end thereof, for the purpose hereinafter described.

As clearly shown in Figs. 2 and 3, it will be seen that the upper end portion of the 10 window frame is provided with a stationary beveled cross-bar 7 adapted to contact with a complementary beveled cross-bar 8 forming the upper end of the upper sash frame 9, and the lower cross-bar or meeting rail 15 of said upper sash is beveled at 10, so as to contact with the complementary beveled cross-bar 11 constituting the upper end of the lower sash frame 12, while the cross-bar forming the lower end portion of said lower 20 sash is so beveled as to rest in contact with the complementary beveled portions 13, 14, 15 and 16 formed on the upper surface of the sill of the window frame, and the meeting rails of the sliding sashes 9 and 12 are provided preferably with two suitable locking 25 means 17, whereby when the sashes are locked together in closed position, the sashes will be forced into such close and rigid contact with each other, and with the window frame, owing to the wedging action of the beveled surfaces at the top, the meeting rails and bottom of the window, as to effectually prevent the entrance of air, dust and other foreign matter into a room, thereby constituting a weather proof window 30 which is an important factor in cold climates, preventing rattling of the sashes, and dispensing with the use of weather strips, as will be readily understood.

40 In each of the upright side portions of the window frame is formed a longitudinal groove in which is fitted a parting strip or rail 17' composed of a stationary upper section 18, and a removable lower section 18', 45 each of said sections being provided at their meeting ends with a complementary beveled portion 19, and a right-angle metallic bearing plate 20, the upper section of said strip or rail being recessed for the reception 50 of a sliding bolt adapted to securely lock the sections together, when the removable section is placed in its proper position in alignment with the upper stationary section 18, the beveled meeting ends 19 permitting the 55 ready removal and replacement of the detachable section when desired. Each section of the parting strip on the reverse side thereof, is also provided with a longitudinal integral lateral extension forming a 60 tongue 20', the upper end of the tongue of the upper section resting in contact with the upper end of the window frame and extending downward to a point in alignment with the lower end of said upper section, while 65 the lower section is provided with a similar

tongue with its upper end terminating at a point near the upper end of said section, and its lower end terminating at its bottom end portion, said tongues being adapted to be snugly fitted into complementary grooves 70 formed in the inner side face of each upright side rail 23 of the upper sash, and the outer side face of each upright rail 24 of the lower sash, the groove in the upper sash extending from the top end thereof and terminating at a point within the sash and near the central portion of the meeting rail while the groove in the lower sash extends from its bottom and terminates at a point within the sash and near the central portion of its 80 meeting rail, said tongues of the parting strip or rail being so fitted into the grooves formed in the sash as to permit the sash frames to freely slide upward and downward thereon, at the same time preventing 85 the access of any cold air into a room owing to their construction and the relative positions they occupy with respect to each other, and to the termination of the grooves at the points named within the sash frames, as will 90 be readily apparent.

As shown in Figs. 1 and 2 it will be perceived that the inner jamb rail or strip at each side of the window frame is composed of an upper stationary section 25 and a 95 lower hinged section 26, each of said hinged sections 26 being adapted to swing outward when it is desired to remove the sashes, or when it is desired to ventilate the room by swinging the lower sash inward and securing 100 it in the position shown. Within a recess formed in the lower end portion of each of the stationary sections 25, is secured a small pulley 27 adapted to receive the sash cords, and thus prevent wear and friction 105 on said cords when the lower sash is adjusted to the position shown, and formed in the inner edge of the lower end portion of each section 25 is a recess 28 for the reception of one end of a bar or link 29 at 110 each side of the window, which is secured by a headed bolt or screw 30 which passes through an opening 31 formed in the bar or link, said bolt or screw serving also to suitably secure the pulley 27, and metallic 115 securing button 32, the latter being adapted to secure the hinged section of the jamb strip or rail in its closed position, the other end of the bar or link 29 being provided with a notched portion adapted to be fitted 120 to a headed pin or screw 33, secured in the recessed portion formed at the upper end of the lower sash. At each side of the window frame seated in a recessed portion 125 thereof and resting substantially flush with the outer face of the frame is suitably and fixedly secured a metallic wearing plate 34 provided with a lateral extension adapted to constitute the upper end of the recess 28 and constituting a stop or anchor 130.

for limiting the upward movement of the bars or links 29, which serve to secure the lower sash in its inward ventilating position, said plate 34 also serving as a wear 5 plate or surface for protecting the window frame from wear and abrasion, which may be caused by the inward and outward movement of the bars or links 29 which are normally seated in a recess formed in the window frame. To prevent the entrance of rain or snow into a room at each side of the window, when the lower sash is adjusted to the position shown in Fig. 2, suitable shields 35 of any desirable material 10 are provided, said shields being substantially triangular in shape with the inner edge of each resting in the grooves formed in each upright side rail of the sash, while the outer edge of each shield is 15 provided with a clip 36, which straddles the tongue formed on the parting strip thereby fixedly securing each shield in such position as to prevent its accidental removal or displacement by gusts of wind, 20 prevents the entrance of rain or snow and forcing the water to run downward and out over the downwardly inclined sill at the bottom of the window. 25

As clearly shown in Fig. 4, the upright 30 rails of both the upper and lower sash frames in each outer edge face thereof is provided with a wide recessed portion 37 adapted to receive the knotted end portion of the sash cord or rope, to which end portion 35 may be secured, if desired, a ring seated within the recess which ring may be secured to a hook placed at any suitable point on the window frame for securing the end of the cord in a convenient position 40 when the cord is removed from the sash, and connecting with the recess 37 is formed a narrow upright groove 38, for the reception of the cord communicating with a groove 39 extending slightly upward and 45 outward, said recess and grooves constituting novel and secure means for fastening the sash cords to the sashes, and facilitating the quick and easy attachment to and detachment from the sash frames of the said 50 sash cords or ropes. Above the groove 39 at one side thereof is formed a guideway for the sash and which causes it to rest in vertical alinement with the pulleys secured at one side of the upper end portion of the slide- 55 ways. Secured within a rectangular shaped recess formed in each outer edge face of the upright rails of the sash frames, near both the upper and lower portion of the recess is a headed screw 40, adapted to receive and 60 secure within the recess a cover plate 41, provided with an elongated recessed portion 42 at its upper end for straddling the upper screw 40 beneath the head, while the shallow recessed portion 43 at the lower 65 end of the plate is adapted to straddle the lower screw 40 thereby securely holding the cover plate in position over the secured end of the sash cord or rope, said plate 41 being preferably provided with an opening 70 44 therethrough for the reception of a finger to facilitate the ready attachment or removal of the plate when desired. 75

It will be perceived that the upper end portion of each outer edge face of the upright rails of the sash frames are recessed at 45 in order to avoid contact with the flanged sides of the rope pulleys in the upper end of the window frame when the sashes are moved to their extreme upward position. 80

The meeting sash bars or rails of each sash are provided with a recessed portion formed at each end of their contact faces, which is adapted to entirely overlap the respective side faces of the parting strip at 85 the juncture or point of connection of the two sections of said strip, with the beveled notched portion 46 thereof, extending over the outer face of the parting strip at its meeting ends, so that when the sashes are in 90 closed position the meeting ends of the parting strip are concealed and an air tight joint is formed. 95

The cross rail or bar forming the lower end of the lower sash being of greater depth than the cross bar forming the upper end of the upper sash, it will be readily obvious that, when it is desired to remove the upper sash from the window for any purpose, it will be simply necessary to slide it downward until it reaches the lower sill of the window, the upper end of the sash will then rest at a point below the stationary section of the parting strip or rail, and the lower section of the parting strip being removed 100 and the hinged section of the jamb strip being open the said upper sash may be easily and readily swung inward into a room for the desired purpose. 105

It will be understood that when my improvements are used in warm climates, both the upper and lower sashes may be adjusted into the desired position within the window frame to furnish a maximum amount of ventilation, or both sashes may 110 be entirely removed, thereby leaving an unobstructed area, without interfering in any respect whatever with the window screen which is usually secured to the outer face of the window frame. 115

Having thus described my invention what I claim and desire to secure by Letters Patent is:—

1. In a window, a frame having a transverse beveled inner surface across its top portion, sashes slidably mounted in the frame, the upper sash having a beveled outer surface formed across its top rail, the meeting rail of each sash being oppositely beveled at their contact surfaces, the bottom 120 125 130 135

portion of the frame having a plurality of bevels formed on its outer surface, and a plurality of bevels formed on the inner surface of the bottom rail of the lower sash 5 adapted to contact with the bevels on said frame, a parting strip composed of two sections locked together at their meeting ends, each section having a longitudinal tongue formed on its reverse side face adapted to 10 engage with grooves formed in the upright side rail of each sash, said grooves and tongues terminating near the top and bottom portion of each sash, whereby a weatherproof window is formed when the 15 sashes are properly locked in their closed position.

2. A window - frame, sashes slidably mounted in said frame, a parting strip fitted to the frame, said parting strip being composed of an upper stationary section and a lower removable section, said upper section having an integral longitudinal outwardly extended tongue formed on its outer face, and the removable section having an integral longitudinal inwardly extended tongue formed on its inner face, said tongues being adapted to engage with longitudinal grooves formed in the upright rails of both sashes and terminating near 30 the top and bottom of each sash, and adapted to form an air-tight connection therewith.

3. A window-frame provided with a parting rail or strip composed of a stationary section and a removable section, each section being beveled at its meeting end, and secured together at the central portion of the window by a sliding bolt, the stationary section being formed with an outwardly extended integral longitudinal tongue formed on its outer face, and the removable section formed with an inwardly extended integral longitudinal tongue formed on its inner face, said tongues being adapted to engage 45 with grooves formed in the upright side rails of both the upper and lower sashes fitted within the said frame and terminating near the top and bottom of each sash.

4. A window frame provided with a parting rail or strip fitted within the frame at each side thereof, said rail consisting of an upper stationary section and a lower removable section, both sections being beveled at their meeting ends, a sliding bolt for locking said sections together, each section having an integral extended longitudinal tongue formed on its reverse side face adapted to engage with grooves formed in sliding sashes fitted within the said frame, 55 said grooves and tongues terminating near the top and bottom portion of each sash.

5. In a window, a frame, an upper and a lower sash slidably mounted in the frame, the upright side rails of each sash having a longitudinal groove formed therein, each

groove terminating at a point near the center of the meeting rail of each sash, and a parting rail fitted in said frame at each side thereof composed of a stationary upper section and a removable lower section locked together at the central portion of the window, each section having an integral extended longitudinal tongue formed on its reverse side face adapted to engage with the grooves in the sliding sashes and form an air tight joint therewith, each tongue terminating near the top and bottom portion of each sash.

6. In a window, a frame, an upper and a lower sash slidably mounted within the frame, the upright side rails of each sash having a longitudinal groove formed within their opposite faces, each groove extending to the opposite end of each side rail and terminating at a point about the center of the meeting rail of each sash, a parting rail fitted to each side of the frame composed of an upper stationary section and a lower removable section, a sliding bolt for locking their beveled meeting ends at the central portion of the window, each section having an integral extended longitudinal tongue formed on its reverse side face, the meeting rail of each sash being constructed so as to overlap and conceal the joint formed by the parting rail, and the grooves in the sashes being so positioned as to slidably engage with said tongues and form an air-tight connection therewith.

7. In a window, a frame, an upper and a lower sash slidably mounted within the frame, the upright side rails of each sash having a longitudinal groove formed within their opposite faces extending from the terminal opposite end of each sash and terminating about the central portion of the meeting rail of each sash, a parting rail consisting of an upper stationary section and a lower removable section, a sliding bolt for locking the sections together, each section having an integral extended longitudinal tongue formed on its reverse side face, and the meeting rail of each sash being recessed and notched at each side thereof so as to overlap the side and front face of said parting rail and conceal the joint formed at its jointed ends, said grooves in the sashes being adapted to slidably engage with the tongues of the parting strip and form an air-tight connection.

8. In a window, a frame, an upper and a lower sash slidably mounted within the frame, a parting rail fitted to each side of said frame composed of a stationary upper section and a removable lower section, a sliding bolt for locking said sections together, an inner jamb rail secured to the frame having a stationary upper section and a hinged lower section, a pulley secured to the lower outer end of the stationary jamb section, a

sash securing link fitted within a recess formed at the lower end of the last named section, a button for securing the jamb sections together, and a bolt for securing said 5 pulley, link and button to the window.

9. In a window, a frame, an upper and a lower sash slidably mounted in said frame, a parting strip composed of an upper stationary section and a lower removable section 10 fitted in the frame, a front jamb rail composed of a stationary section and a hinged section secured to the frame, a pulley secured within a recess formed in the lower outer corner of the stationary jamb section, a sash 15 securing link pivotally secured within a recess formed in the inner lower portion of said stationary jamb section, and a button for securing the jamb sections together, said pulley, link and button being secured to the 20 window by a single securing bolt.

10. In a window, a frame, an upper and a lower sash slidably mounted within slideways formed in said frame by sash cords and weights, a pulley mounted at the upper 25 end and at one side of the center of each slideway for the reception of the sash cords, and a sash cord firmly secured within the upright rail at each side of each sash and emerges from one side of the central portion 30 of said rail so as to rest in vertical alinement with said pulley at one side of each of the slideways.

11. In a window, a frame, an upper and a lower sash slidably mounted in the slideways 35 formed in the frame, sash cords with weights secured to each sash, a pulley mounted at the upper end and at one side of the center of each slideway, and a sash cord secured to the upright rail at each side of 40 each sash, each cord being retained in a recess formed in the upper end portion of each sash and emerges from said recess at one side of the central portion of the upright rail for holding the cord in vertical alinement with 45 the said pulleys.

12. In a window, a frame, an upper and a lower sash slidably mounted in said frame, sash cords secured to each sash, means formed in the upper portion of the outer 50 edge face of the upright rails of each sash for firmly securing the sash cords thereto, a pulley secured to the upper end of the frame at one side of the center of a slideway, and means formed on the outer edge 55 face at one side of the central portion of each upright rail of the sash for retaining the sash cord in vertical alinement with the pulley.

13. In a window, a frame, an upper and a 60 lower sash slidably mounted in said frame, sash cords secured to each sash, the upright rails of each sash being formed with a lower widened recess for the reception of the knotted end of the cord, a narrow vertical recess for the reception of the

cord communicating with the first named recess, and a recess formed substantially at a right angle to the last named recess, said recesses being so formed as to securely lock the sash cord to each of said upright rails. 70

14. In a window, a frame, an upper and a lower sash slidably mounted in said frame, sash cords secured to each sash, the upright rails of each sash being provided with a lower wide recess forming a shoulder within 75 the rail adapted to receive the knotted end of the cord, a narrow recess formed above the wide recess and communicating therewith for the upright portion of the cord, and an outwardly inclined recess through which the 80 cord is passed communicating with the narrow recess and connecting with a recess formed in the outer upper corner portion of each upright rail, said recesses being so formed within the said rails as to firmly secure the sash cords to the sash and retain it in vertical alinement at one side of each sash. 85

15. In a window, a frame, an upper and a lower sash slidably mounted in said frame, sash cords secured to each sash, vertical 90 grooves formed in the upright rails of each sash, a parting rail having a stationary upper section and a removable lower section, each section having an integral extended longitudinal tongue formed on the reverse 95 side face thereof for engagement with said grooves, slideways formed in the frame, a sash cord pulley mounted at the upper end at one side of each slideway, and a recess formed in the outer edge of each upright 100 side rail near the top thereof to prevent contact with the flanges of said pulleys when the sashes are moved to their upward limit.

16. In a window, a frame, an upper and a lower sash slidably mounted in said frame, 105 sash cords secured to the upright rails of each sash, a vertical groove formed in the opposite side face of each upright rail, a parting rail consisting of an upper stationary section and a lower removable section, 110 each section having an integral vertical extended tongue, and a weather shield fixedly secured within the grooves of the lower sash and to said tongue extending to the bottom of said lower sash. 115

17. In a window, a frame, an upper and a lower sash slidably mounted within said frame, sash cords secured to each sash, a vertical groove formed in the opposite side face of the upright rails of each sash, a parting rail having a removable lower section 120 provided with an integral vertical tongue formed on its inner side face, a weather shield with its inner edge resting in the groove formed in the lower sash when said sash is adjusted to an inward inclined position, and its outer edge secured to the said tongue. 125

18. In a window, a frame having a transverse inner beveled surface portion at its 130

upper end, an upper and a lower sash slidably mounted in the frame, the upper end rail of the upper sash being beveled on its outer surface to contact with said beveled portion of the frame, the meeting rail of each sash having oppositely beveled faces adapted to contact with each other, a plurality of outwardly beveled surfaces formed at the bottom of the window frame, the bottom rail of the lower sash having a plurality of inwardly beveled surfaces adapted to contact with the plurality of outwardly

beveled surfaces, the upright rails of each sash having a vertical groove formed therein terminating within the sash, a parting strip 15 formed with integral extended vertical tongues adapted to engage with said grooves, the entire structure coacting together to form a weather-proof window, when the sashes are locked by proper locking means 20 in their closed position at the meeting rails thereof.

ROBERT NORRIS.
